(57) **CLAIM**

The ornamental design for a shaft clamp for a chain hoist of a counterbalancing mechanism, as shown and described.

DESCRIPTION

FIG. 1 is a top perspective view of the shaft clamp;
FIG. 2 is a front view thereof;
FIG. 3 is a rear view thereof;
FIG. 4 is a left-side elevational elevation view thereof;
FIG. 5 is a right-side elevational view thereof;
FIG. 6 is a top view thereof;
FIG. 7 is a bottom view thereof; and,
FIG. 8 is an alternate top perspective view thereof, the shaft clamp being shown in relation to an exploded view of a chain hoist of a counterbalancing system.
The portions shown in broken lines form no part of the claimed design.

1 Claim, 8 Drawing Sheets
